PIE PLATE

Merrill A. Grogel, Henrico County, Va., assignor to Reynolds Metals Company, Richmond, Va., a corporation of Delaware

Filed July 31, 1963, Ser. No. 76,049

Term of patent 14 years

(Cl. D44—1)

FIG.1

FIG.2

FIG.3

FIG.4

FIGURE 1 is a top perspective view of a pie plate, showing my new design, wherein the bottom wall is embossed in the pattern shown.

FIGURE 2 is a top view of the pie plate of this invention.

FIGURE 3 is a cross-sectional view taken on line 3—3 of FIGURE 2.

FIGURE 4 is a top plan view of another form of pie plate showing my new design, wherein the bottom wall is plain and unembossed.

The common design present in the embodiments of FIGURES 1 and 4 includes a curved side wall of the pie plate wherein the wrinkled pattern in the curved side wall includes frusto oblong units around the same wherein a progression begins from a point at the bottom of one frusto oblong unit and gradually lengthens to bisect such

unit and then recedes toward the top of such unit while retaining the point at the bottom thereof, such progression in the frusto oblong units being repeated twice about the perimeter of the plate wall.

I claim:

The ornamental design for a pie plate, as shown and described.
